BUILDING CONSTRUCTION

Merle D. Bishop, Berkeley, Calif.

Application May 3, 1940, Serial No. 333,140

4 Claims. (Cl. 20—2)

This invention relates to building construction and more particularly to an assembly of particular units of building material, the pieces of which may be made at a mill and fabricated into building construction with facility and economy.

Among the objects of the invention are to provide an assembly of board building construction units in which the parts are relatively contoured and arranged so that a building may be constructed strongly, efficiently and economically without employment of studding or roof rafters. Another object is to provide a board building structure, from which the usual skeleton frame may be eliminated. A further object is to provide an assembly of fabricated building units coordinated to give strength and rigidity to a building, and portions of which may be pre-assembled in pre-fabricated units.

With the foregoing and other objects in view, the invention consists in the arrangement and mechanical cooperation of parts herein described, and in the structure fabricated therefrom, it being understood that variations in the form, proportion, size and details of construction of the individual elements may be resorted to within the scope of the appended claims without departing from the spirit or sacrificing any of the advantages of the invention.

To more clearly comprehend the invention, reference is directed to the accompanying drawings wherein:

Fig. 1 is a vertically transverse view, partly in section, of a representative type of construction employing the invention, wherein a wall is parallel to roof eaves.

Fig. 2 is a vertically transverse section of an employment of elements of the invention, wherein in a wall is perpendicular to roof eaves, the interior wall being shown in fragment.

Fig. 3 is an enlargement of part of structure shown in Fig. 1.

Fig. 4 is also an enlargement of part of structure shown in Fig. 1.

Fig. 5 is a longitudinally transverse section of a corner joining of wall members.

Fig. 6 is an enlarged transverse horizontal section showing detail of wall construction.

Fig. 7 is a fragmentary transverse vertical section of a double-hung window construction.

Fig. 8 is a fragmentary vertical transverse section of casement window construction.

Fig. 9 is a fragmentary perspective view of one form of header plate.

Referring to the drawings in which like characters of reference indicate corresponding parts

in the several views, 10 is a foundation of suitable material such as poured cement having reinforcing rods 11, and tie bolt 12 which holds mud sill 13 longitudinally of the foundation. 10 Underpinning 14 is provided with a header 15 upon which joist stringer 16 rests. Floor joists 17 extend transversely under any suitable flooring 17a. A water table 18 may be employed spaced the usual distance adjacent the foundation. As described thus far, the structure may be entirely conventional. The milled pieces for supporting side and end walls are of elongated boards 19 which are relatively thick as compared to their width. For purposes of substantial construction under this invention, it has been found efficient if the wall boards 19 are of a thickness of $1\frac{1}{8}$ inches by a width of $7\frac{1}{8}$ inches. The boards 19 have a tongue 20 and groove 21 at respective opposite longitudinal edge faces, the tongue and groove being of a width to accommodate bored recessed dowel holes 23 in register in adjacent board edges, but which extend only partially transversely of the boards 19 (see Fig. 6), so as to leave a substantial portion of the board transversely centrally in its original condition without dowel recesses therethrough so as not to weaken the wall throughout a line defined by a continuous tie rod or dowel pin, which would be the case if the dowel pin was continuous 20 through a plurality of juxtaposed boards 19. The holes 23 receive dowel pins 22. The relative thickness and width of the boards 19 and the doweling thereof permits the fabrication of buildings of ordinary size with a total elimination 25 of studding or other skeleton frame. The boards 19 may be vertically erected by securing them to the stringer 16 in any suitable manner, such as by nailing and when in vertical position, in dowelled edge-to-edge relationship, they are 30 capped by a header plate 24 which is of sufficient length to cap a plurality of the boards 19, and preferably of a length to extend from one end to the other of a wall. The header plate is provided at one face with a groove 25, the groove 35 being of sufficient width to snugly receive the ends of boards 19. Where the header plate receives bearing of a roof of inclined plane, as in Fig. 1, the opposite or upper face 26 of the header plate is inclined at substantially an angle 40 similar to that of the roof, an incline of approximately 20° to the horizontal being normally satisfactory. This provides a header plate narrowed at an outer side 27, and broader at the inner side 28, so that when siding 29 is employed 45 to cover the boards 19, such siding may extend

closely adjacent the roof, and the inner side 28 of the header plate may have formed integrally therewith a molding for decorative purposes on the inside of a room. Where juncture of roof and side wall is normal in transverse section, as in Fig. 9, the upper face 26^a conforms to the normal angle.

The boards 19 overlap at the corners of structures and may be secured by nails or by screws as at 30. At the corners a suitable corner molding 31 may also be employed if desired. The roof boards 19^a are also preferably formed of similar thickness and width and with similar doweling as the side wall boards 19, such construction eliminating roof rafters. The roof boards 19^a are inclined and at their adjacent opposing ends they are connected by an elongated ridge member 32 normal to the longitudinal dimension of the boards. The ridge member 32 has converging or keystone sides 33 which are of a depth similar to the thickness of the roof boards 19^a. At the lower or converging end of the sides 33 the ridge member is flared outwardly providing an angle 34 to receive and support the lower edge of the roof-board end, and also to provide a sub-joined molding 35 for covering the juncture of the roof boards and ridge. The sub-joined molding 35 also provides an interior finish to the peak of the roof. The ridge 32 is preferably arched at its upper face as at 36 so as to provide a continuous smooth surface, in conjunction with the outer face of the roof boards to facilitate application of roofing or insulating material, such as a layer of felt 37 and flexible roofing paper 38. The boards 19 and 19^a may be secured to their respective bearing supports in any suitable manner, such as by nails 39. If it is desired to eliminate the header plate at end walls the boards 19 of such walls may be nailed or screwed directly to the transverse floor joists 17 at the bottom and to the side edge of the end roof board. However, it is preferred that header plate as shown in Fig. 9 be employed, especially if it is desired that the roof be provided with an overhanging eave beyond the end wall, as the use of such header plate adds greatly to the rigidity of the structure and provides uniform interior molding finish on all walls.

In Fig. 9, due to the normal reaction of the upper face of the header plate, the inner and outer side walls 27, 28 of the plate will be substantially similar.

Windows and doors of suitable type may be provided in connection with such construction assembly. The frame of the doors and the casing of the windows are formed of strip material which is T-shaped in cross-section with the stem 40 of the T delineating the window casing or the door frame, and the integral crossbar 41 of the T overlapping the sash of the window, or the door proper; in either case, having one leg of the crossbar overlying the junction of the wall and the frame or casing, and the other leg of the crossbar providing a slide strip for the sash of a sliding window or a stop for a door or casement window, as shown at 42 in Fig. 7 and Fig. 8.

As shown at 43 in Figs. 7 and 8 a sill for windows may extend slightly beyond the outer wall of the building, as is usual.

In the event it is desired to provide interior walls of the same type as the outer walls and roof, as above described, such inner walls may employ the same type of header plate as is employed with the outer walls dependent on whether

the inner wall parallels the side wall with the inclined header plate, or parallels the end walls with the normal header plate.

By this type of structure, buildings of very substantial size and rigid construction may be prepared in knock-down form with holes drilled for receiving screws instead of nails for fastening the parts together; it may be readily erected at any desired place and may likewise be readily dismantled and moved to another location. Large sections of side wall, roof and inner walls may be joined and dowelled together as fabrication units at the factory or lumber mill, cleated by cleats 44 lightly nailed thereto as at 45, and shipped to point of use where they may be erected as single units, the header plates mounted thereon and the ridge member installed, the parts being secured by pre-bored screw holes and thus a complete and rigid building structure constructed at a minimum of expense of both material and labor. Experience has demonstrated that this type of fabricated structure and the assembly of parts therefor is entirely practical for rooms in which there are walls not exceeding approximately forty-five feet in length or width. Structures have actually been built employing the assembly parts herein described and have been approved by building regulating departments or bureaus in cities having a high standard of requirements for building construction.

Having thus described my invention, I claim:

1. A fabricated building adapted for portability, including exterior wall boards comprising a plurality of elongated boards having longitudinally a tongue at one edge and a groove at the opposite edge, the respective tongue and groove of adjacent boards inter-fitting, the wall boards being of sufficient thickness to furnish the wall support for the roof, said boards having at opposite longitudinal edges a plurality of recessed holes transversely therein registering relatively in opposed edges of adjacent boards, said recessed holes extending a portion of the way only transversely of the width of the board, leaving a centrally transverse longitudinal portion of the board free of such recessed holes, dowel members for fitting in said holes and extending from within one board into an adjacent board, an elongated header plate adapted for extending along the uppermost edges of the side exterior wall boards, said plate having in its lower face a groove of a width for snugly receiving the uppermost edge of the exterior wall boards, the upper face of said header plate being inclined transversely to the groove, a ridge rafter having downwardly converging keystone sides flared outwardly adjacent its base and providing a shoulder for supporting an end of juxtaposed roof boards, and roof boards having one end portion secured to said plate and the other end abutting the keystone sides of the ridge rafter and resting on the shoulder of the said rafter.

2. A fabricated building adapted for portability, including exterior wall boards comprising a plurality of elongated boards having longitudinally a tongue at one edge and a groove at the opposite edge, the respective tongue and groove of adjacent boards interfitting, the wall boards being of sufficient thickness to furnish the wall support for the roof, the opposite edge faces of said boards having a plurality of holes recessed therein transversely and substantially in the plane of the tongue and groove portions thereof, said holes registering relatively in opposed edges of adjacent boards, said recessed holes extending

a portion of the way only transversely of the width of the board leaving a centrally transverse longitudinal portion of the board free of such recessed holes, dowel members for fitting in said holes and extending from within one board into an adjacent board, an elongated header plate adapted for extending along the uppermost edge of the side exterior wall boards and having in its lower face a groove of a width for snugly receiving the uppermost edge of the exterior wall boards, the upper face of said header plate being inclined transversely to the groove, a longitudinal side of the plate having integral moldings thereon to provide an integral interior finish molding, a ridge rafter having downwardly converging keystone sides flared outwardly adjacent the base and providing a shoulder for supporting an end of juxtaposed roof boards, and roof boards having one end portion secured to said plate and the other end abutting the keystone sides of the ridge rafter and resting on the shoulder of the said rafter.

3. A fabricated building adapted for portability, including exterior wall boards and roof boards, said wall and roof boards comprising elongated boards having longitudinally a tongue at one edge and a groove at the opposite edge, the respective tongue and groove of adjacent board edges inter-fitting, the wall boards being of sufficient thickness to furnish the wall support for the roof, the opposite edge faces of both wall and roof boards having a plurality of holes recessed transversely therein registering relatively in opposed edges of adjacent boards, said recessed holes extending a portion of the way only transversely of the width of the board leaving a central transverse longitudinal portion of the board free of such recessed holes, dowel members for fitting in said holes and extending from within one board into an adjacent board, an elongated header plate adapted for extending along the uppermost edge of the side exterior wall boards, said plate having in its lower face a groove of a width for snugly receiving the upper-

most edge of the exterior wall boards, the upper face of said plate being inclined transversely to the groove, a ridge rafter having downwardly converging keystone sides flared outwardly adjacent its base and providing a shoulder for supporting an end of juxtaposed roof boards, said roof boards having one end portion secured to said plate and the other end abutting the keystone sides of the ridge rafter and resting on the shoulder of the said rafter.

4. A fabricated building adapted for portability, having exterior walls of vertically disposed boards and having roof boards supported thereby, said wall and roof boards being elongated and each having longitudinally a tongue at one edge and a groove at the opposite edge, the wall boards being of sufficient thickness to furnish the wall support for the roof, the opposite edge faces of both wall and roof boards having a plurality of holes recessed therein transversely and substantially in the plane of the tongue and groove portions thereof, said holes registering relatively in opposed edges of adjacent boards, said recessed holes extending a portion of the way only transversely of the width of the board leaving a centrally transverse longitudinal portion of the board free of such recessed holes, dowel members for fitting in said holes and extending from within one board into an adjacent board, an elongated header plate adapted for extending along the tops of exterior wall boards, and having in its lower face a groove of a width for snugly receiving the upper ends of the wall boards, the upper face of said plate being inclined transversely to the groove, a ridge rafter having downwardly converging keystone sides flared outwardly adjacent the base and providing a shoulder for supporting an end of juxtaposed roof boards, said roof boards being of sufficient thickness to be self-supporting and having one end portion secured to said plate and the other end abutting the keystone sides of the ridge rafter and resting on the shoulder of the said rafter.

MERLE D. BISHOP.
